UNITED STATES PATENT OFFICE

2,107,758

PROCESS FOR AVOIDING THE OVERCHARGING OF DRIVES FOR RAYON CENTRIFUGES

Erich Knechtel, Sydowsaue, near Stettin, Germany, assignor to North American Rayon Corporation, a corporation of Delaware

Application March 4, 1931, Serial No. 520,162
In Germany March 10, 1930

5 Claims. (Cl. 18—54)

In the manufacture of rayon, especially viscose rayon, according to the so-called centrifuge or spinning pot process, where spinning baths are used containing sulphuric acid and salts and under certain conditions also organic matters, certain difficulties have arisen when the spinning pots are run at a great number of revolutions. This is particularly the case if the spindle speed exceeds 5,000, for instance at from 7,000 to 12,000 revolutions per minute, where it has been found that in a continuous operation during which, in the course of several hours, the spinning pot is gradually filled with fresh rayon, the necessary driving forces increase in an incomprehensible manner which, especially in the case of electric motors, may cause dangerous over-loadings. It has been found that this increase and additional load during such a spinning period is hardly caused by an increased friction of the gears, or by the larger amount of rayon in the spinning pot. A more thorough investigation shows that with this large number of revolutions as required by the high spinning speed, and more so with the manufacture of a strong warp twist, crystals are caused by the evaporation of spinning bath solutions out of the spinning pot. The evaporation is accelerated by the great surface speed of the pot in the surrounding atmosphere. Further tests have shown that these salt crusts make the surface of the pot uneven and thus cause a larger amount of friction in the air, which again causes the above over-load.

According to the present invention the formation of these salt crusts is eliminated, or the 35 deposits are continuously or intermittently removed. This may be done in different ways.

Thus, the spinning pots can be sprayed continuously or intermittently with liquids, such as warm water, during the working time. This water 40 is able to dissolve the salt crusts immediately after they begin to form.

Another method of procedure is to maintain such atmospheric conditions in the spinning pot chambers as will not allow the formation of salt 45 crusts, e. g. by maintaining an especially high air humidity, or by introducing wet vapor into the spinning pot chambers.

Another form of this process is to spray warm water of 30—40° C. by means of a nozzle in a fan-like form in tangential direction on the outer mantle of the centrifuge pot in the direction of its rotation.

In the drawing accompanying this application, 55 Figure 1 is a cross sectional view through the

chamber of a spinning centrifuge illustrating the use of my invention.

Fig. 2 is a plan view of a plurality of spinning chambers illustrating the use of my invention with the covers of said chambers removed. 5

In the drawing in which like numerals of reference indicate like parts, 1 represents the vertical walls of the spinning chambers and 2 indicates the bottom partition.

The partition 2 has an opening 3 through which 10 the spinning spindle 4 projects. The spinning pot 5 is supported and rotated by the spindle 4. A cover 6 having an opening 7 for the insertion of a thread guide tube (not shown) is illustrated in Figure 1. 15

In order to eliminate the formation of the aforementioned salt crusts with consequent danger of overloading the rotating means, the pots are sprayed during rotation with liquid which is brought through the spinning chamber by means 20 of a supply pipe 8. Branch pipes 9 having nozzles 10 are supported on the supply pipe 8 and are positioned in such a manner as to send a fan shaped spray tangentially against the side of the spinning pot. This eliminates the formation of 25 crystals with the resultant danger to the spinning operation.

From the foregoing description taken in connection with the accompanying drawing, it is believed that the operation and advantages of my 30 invention will be apparent to those skilled in the art.

Having now fully set forth my invention as required by the patent statutes, what I desire to claim is:

1. In the method of collecting wet spun filaments in a driven spinning pot, the step of submitting the outer surface of the pot to a spray of liquid in a direction tangential to the said surface and in the direction of rotation thereof while the centrifuge is in operation. 35

2. In the method of collecting spun filaments in a driven spinning pot, the step of submitting the outer surface of the pot to a fan-shaped spray of liquid in a direction tangential to the said surface and in the direction of rotation thereof while the centrifuge is in operation. 45

3. In the method of collecting spun filaments in a driven spinning pot, the step of submitting the outer surface of the pot to a periodic spray 50 of liquid in a direction tangential to the said surface and in the direction of rotation thereof while the centrifuge is in operation.

4. In the method of collecting spun filaments in a driven spinning pot, the step of submitting 55

the outer surface of the pot to a spray of liquid maintained at a temperature between about 30° and 40° C. in a direction tangential to the said surface and in the direction of rotation thereof while the centrifuge is in operation.

5. In the method of collecting spun filaments in a driven spinning pot, the step of submitting

the outer surface of the pot to a spray of liquid in a direction tangential to the said surface and in the direction of rotation thereof while the centrifuge is in operation the said spray being discontinued during a part of the operation of the 5 centrifuge.

ERICH KNECHTEL.
